Application June 9, 1949, Serial No. 3,135

Term of patent 7 years

(Cl. D9—2)

To all whom it may concern:

Be it known that I, Mathew J. Marty, a citizen of the United States, residing at Chicago, in the county of Cook and State of Illinois, have invented a new, original, and ornamental Design for a Combination Brush Drip Guard and Hanger, of which the following is a specification, reference being had to the accompanying drawing, forming a part thereof.

In the drawing:

Figure 1 is a plan view of a combination brush drip guard and hanger showing my new design;
Figure 2 is a side elevational view thereof;
I claim:

The ornamental design for a combination brush drip guard and hanger, as shown.

MATHEW J. MARTY.

MATHEW J. MARTY

It is hereby certified that errors appear in the above numbered patent requiring correction as follows:

In the drawings, strike out Figure 4 thereof, and insert instead the following:

in the printed specification, first column, line 14, after the word "thereof" and before the period, insert showing the combination brush drip guard and hanger assembled on a paint brush. The latter is shown in broken lines for illustrative purposes only; and that the said Letters Patent should be read with these corrections therein that the same may conform to the record of the case in the Patent Office.

Signed and sealed this 18th day of July, A. D. 1950.
